(57) **CLAIM**

The ornamental design for a calculator pencil box, as shown and described.

DESCRIPTION

FIG. 1 is a perspective view of a calculator pencil box showing my new design;

FIG. 2 is a top plan view thereof;

FIG. 3 is a front elevational view thereof;

FIG. 4 is a right side elevational view thereof, which is a mirror image of the left side;

FIG. 5 is a rear view thereof; and,

FIG. 6 is a bottom view thereof.

The broken line showing of numbers in FIGS. 1 and 2 is included for the purpose of illustrating portions of the calculator pencil box and forms no part of the claimed design.
